FUSED CUTOUT

George L. Carlisle, Greensburg, Pa., assignor, by
mesne assignments, to Railway and Industrial
Engineering Company, Greensburg, Pa., a cor-
poration of Delaware

Original application March 13, 1935, Serial No.
10,949, now Patent No. 2,088,152, dated July
27, 1937. Divided and this application Febru-
ary 12, 1937, Serial No. 125,503

20 Claims. (Cl. 200—114)

This invention relates to fused cutouts and
more particularly to enclosed cutouts.

This application is a division of my copending
application Ser. No. 10,949, filed March 13, 1935,
on which Patent No. 2,088,152 was issued on July
27, 1937, which discloses and claims, generically,
the enclosed type of dropout fuse hereinafter de-
scribed and specifically claimed.

An object of this invention is to provide an
enclosed fused cutout in which the fuse assembly
is retained in operative position between spaced
terminals only so long as the fuse unit remains
intact, and drops into an inoperative position
upon the blowing of the fuse unit. An object is
10 to provide an enclosed dropout fused cutout in-
cluding a housing and a pivotally supported door
for closing the housing, the fuse assembly being
supported by the door and, in turn, supporting
the door in closed position only so long as the
15 fuse unit remains intact. A further object is to
provide a fused cutout including a housing in
which spaced terminals are mounted, a fuse as-
sembly adapted to be supported by said termi-
nals and including elements movable upon a
20 blowing of the fuse unit to release the fuse as-
sembly from the upper terminal, and a door for
the housing; the fuse assembly being supported
by the door and, in turn, supporting the door in
closed position so long as the fuse unit remains
25 intact.

These and other objects and advantages of the
invention will be apparent from the following
specification when taken with the accompanying
drawings in which:

30 Fig. 1 is a vertical section through an embodi-
ment of the invention;

Fig. 1a is a fragmentary perspective view, part-
ly in section, of a fuse unit;

Fig. 2 is a fragmentary section showing the
40 latching terminal and latch in opening position;

Fig. 3 is a side elevation of the assembly;

Fig. 4 is an inside view of the door and fuse
assembly;

Fig. 5 is a front view, with parts in section, of
45 the fuse box;

Figs. 6 and 7 are sections on lines 6—6 and
7—7, respectively, of Fig. 4; and

Figs. 8 and 9 are perspective views, respectively,
of the lower and the upper terminal members.

50 In the drawings, the reference numeral 30
identifies a housing of ceramic or other insulating
material that is carried by a supporting strap 30
that, preferably, is so shaped that the casing or
housing has a slight forward inclination to facili-
55 tate the automatic dropping of the door or clo-

sure 31 when the fuse blows. One or both side
walls of the casing are provided with hooded
openings 32 for the introduction of the wires
which are to be secured to the upper and lower
terminals of the fused cutout.

The upper terminal comprises a substantially
rigid casting of approximately U-form, the central
portion 33 of the casting being rigidly bolted
to the back wall of the casing and the spaced
legs 34 of the casting terminate in notched ends
10 that provide downwardly opening seats 35, the
upper ends 36 of the terminal legs being for-
wardly inclined to guide the end of a fuse assem-
bly into the seats.

The lower terminal is also of approximately
U-shape and has a central section 37 which is
rigidly secured, at its upper end, to a plate 38 of
bronze or other appropriate resilient material,
and a stud bolt 39 passes through the spring
plate 38 and lower portion 40 of the terminal to
mount these parts on the back wall of the cas-
ing. The nut 41 is not drawn down tightly on
bolt 39 and the adjacent portion 40 of the ter-
minal is convex, thus permitting a limited rock-
ing movement of the terminal upon the bolt. 25
The side arms of the terminal 42 are deeply
notched by arcuate slots 43 to provide a pivotal
seat for the fuse assembly. Both terminals are
provided with tubular portions 44 into which
screws 45 extend to clamp the conductors to the
30 terminals. A name plate 46 may be secured to
the lower terminal.

The door 31 has an integral pull ring and is
preferably formed of a molded synthetic resin,
the inner face of the door being deeply grooved
35 to provide a recess, between the opposed flanges
47, in which the expulsion tube 48 is mounted.
The upper conductive collar 49 is fixed to the tube
48 and has lugs 50 which are fixed to flanges 47
by screws. The inner side of collar 49 has a pair
40 of ears 51 in which the cover 52 is pivotally
mounted, the cover having a latch pin or cross-
bar 53 which engages in the seat 35 of the upper
terminal to retain the door in closed position so
45 long as the cover 52 is closed upon the upper end
of the expulsion tube.

The lower conducting member is an arcuate
strap 54 which is bolted to the cover 52 and has
extensions or hubs 55 for pivotally mounting the
door and fuse assembly in the journal slots 43 of 50
the lower terminal. The strap carries a bolt
and wing nut 56 for clamping the lower end of the
removable fuse to the strap. A washer having
an extension 57 is preferably provided to prevent
any loosening of this clamped connection, the 55

extension being received between spaced ears on the lower face of the strap. The fuse may be of the explosive type, Fig. 1a, and take the form of a cartridge having a conductive base 20 and insulating shell 21 housing an explosive charge 22 that surrounds the ignition wire 23. The ignition wire is connected between the base 20 and a terminal wire 24, and the parts are retained in place by a wad 25 and wax plug 26.

10 The pivotal axis of the cover 52 of the fuse assembly is so positioned, with respect to the latch pin 53 and the hubs 55, that pressure exerted along the plane passing through these parts tends to hold the cover in closed position. The 15 spacing of the terminal seats is slightly less than the distance from the lower face of hubs 55 to the upper face of the latch pin 53 when the cover is closed. The lower terminal is therefore rocked downward, against the force of the spring plate 20 20 38, when the door 31 is moved into closed position. The door may be readily closed, however, by a quick upward swing about the hubs 55, and the spring plate 38 then yieldingly locks the door in closed position.

25 When the fuse blows, the pressure within the expulsion tube 48 rocks the cover 52 into open position, as shown in Fig. 2, and this movement carries the pivot point of the cover through a plane which extends through the latch seats 35 and the journal slots 43, thus allowing the momentarily increased stress in the spring plate 38 to cooperate with gravity to force the door 31 into open position. The dotted lines in Fig. 1 illustrate the door in an intermediate position but it 30 35 will be understood that the door swings into a vertical position when fully open. To refuse the device, the door is lifted from the lower terminal, the broken fuse wire and the cartridge are removed, and the new fuse cartridge is inserted without removing the expulsion tube from the door.

40 The contact surfaces of the conducting members on the expulsion tube and on the terminals may be machined to somewhat different curvatures to provide line contact engagements. The 45 door and fuse assembly constitute the blade member of a fused switch since the door may be opened by a fuse puller inserted in the ring of door 31 to open the circuit between the upper 50 and lower terminals.

55 While I have described a construction including an explosive type of fuse and releasing latch which eliminates all mechanical strain on the fuse element, it will be apparent that the fuse assembly may be of the so-called toggle lever type in which the assembly is held in operative position between the spring-pressed terminals only so long as the fuse unit remains intact.

60 The invention has a number of advantages over prior types of enclosed cutouts. The automatic dropping of the fuse assembly provides a wide separation of the conductive elements which results in a positive interruption of the circuit, and the dropping of the door affords a visual indication which facilitates the identification of the particular circuit that has been opened by the blowing of a fuse unit.

65 While I have described a preferred embodiment of the invention, it is to be understood that changes may be made in the construction of the several parts, and in their relative sizes, shapes and relationships without departure from the spirit of my invention as set forth in the following claims.

I claim:

1. A fused cutout comprising an insulating casing having an open front, a pair of vertically spaced terminals supported by and within said casing, means on the lower terminal for removably and pivotally supporting a fuse assembly, a fuse assembly pivotally mounted on the lower terminal and including an upper conductive member for engagement with the upper terminal, and a door secured to said fuse assembly 10 for closing said casing when the fuse assembly is in operative position between said terminals; said fuse assembly including a fuse unit and means displacing upon the blowing of said fuse unit for releasing said fuse unit from the upper 15 terminal.

2. The combination with a pair of vertically spaced terminals, and a dropout fuse assembly pivotally supported by the lower terminal and maintained in engagement with the upper terminal only so long as the fuse unit remains intact, of a casing of insulating material having an open front and means supporting said terminals on the rear wall of the casing, and a door for the open front of said casing secured to said fuse 20 25 assembly, whereby said door drops automatically to open position upon the blowing of the fuse unit.

3. In a dropout fused cutout, a casing of insulating material having an open front, means for supporting said casing in forwardly inclined position, a pair of vertically spaced terminals carried by the rear wall of the casing, means on the lower terminal for removably and pivotally supporting a fuse assembly, spring means associated with one terminal for urging said terminals towards each other, and a fuse assembly adapted to be pivotally supported on the lower terminal; said assembly including an expulsion tube, a conductive member at each end of said tube for electrical connection to the respective terminals, a fuse unit connected between said conductive members, means displaceable upon the blowing of the fuse unit for releasing the upper conductive member from the upper terminal, and a door connected to said fuse assembly for closing the open front of said casing when said fuse assembly is in operative position between said terminals.

4. A dropout fuse as claimed in claim 3, where- 50 in the engaging surfaces of said terminals and said conductive members are surfaces of different curvature, whereby the contact engagement of cooperating surfaces is restricted to less than a full surface engagement.

5. An enclosed cutout comprising a casing of insulating material having an open front, a pair of vertically spaced terminals supported by the rear wall of said casing, a spring plate for urging one terminal towards the other, means on the lower terminal for pivotally supporting a fuse assembly, a fuse assembly pivotally supported on said lower terminal and including an upper conductive member for wedging engagement with said upper terminal, a fuse included in said as- 60 sembly and electrically connected between said upper conductive member and a lower conductive member engaging said lower terminal, and a door carried by said fuse assembly for closing said casing when said fuse assembly is in operative po- 65 sition between said terminals.

6. An enclosed cutout as claimed in claim 5, wherein said upper terminal is a rigid unit rigidly secured to said casing, and said lower terminal is secured to said spring plate, and means is pro- 70 75

vided for pivotally securing said spring plate to said casing.

7. In a circuit breaker, the combination with a vertically arranged tubular insulating member having conductive members at the opposite ends thereof, a fuse extending through said insulating member and electrically connected between said conductive members, a closure for the upper end of said insulating member, said closure retaining the adjacent end of said fuse in engagement with the associated conductive member, and supporting means on said conductive members for reception in a pair of terminal seats, of a pair of vertically spaced terminals having portions for defining seats which open towards each other for receiving the respective supporting means of said conductive members, the lower terminal including spring means yieldingly urging said seats towards each other to exert a clamping force upon the insulating member seated between the same, and means actuated by the blowing of said fuse to effect a relative displacement of one supporting means and its associated seat to initiate the removal of said insulating member from the upper terminal seat, whereby the clamping force exerted by said spring means cooperates with gravity to effect a rapid removal of the insulating member from the upper terminal seat.

8. A circuit breaker of the type including a casing within which terminals are mounted in vertically spaced relation, and the door of said casing carries a fuse assembly, said fuse assembly having portions engaging seats on the respective terminals, characterized by the fact that the seats on said terminals open towards each other and said terminals include means for yieldingly urging said seats towards each other to clamp the fuse assembly between said terminals, and said fuse assembly includes means actuated by the blowing of a fuse for displacing the upper end of said fuse assembly for its cooperating terminal seat, whereby the door of said casing may drop to open position.

9. In a fused cutout, a casing of insulating material, a pair of vertically spaced terminal members within said casing, and a fuse assembly; said fuse assembly comprising a door for said casing, an expulsion tube mounted on said door, conductive members at the opposite ends of said tube for engagement with said terminal members, a fuse within said tube, said fuse having an enlarged head at its upper end and a conducting wire extending from the fuse through the lower end of the tube for connection to the lower conductive member, and a closure for the upper end of said tube, said closure being movably supported on the upper conductive member and in engagement with said enlarged head of the fuse.

10. In a fused cutout, a casing of insulating material having an open front, a pair of vertically spaced terminals within and supported by the rear wall of said casing, one of said terminals including spring means urging said terminals towards each other, and means on the lower terminal for pivotally supporting a fuse assembly, of a fuse assembly; said fuse assembly comprising a door for the open front of said casing, an expulsion tube mounted upon said door, conductive means at the opposite ends of said tube for engagement with said terminals, a fuse within said tube, said fuse having an enlarged head at its upper end and a conductive wire extending through said tube for connection to said lower conductive means, said upper conductive means including a closure for retaining the enlarged

head of said fuse within said tube and for engagement with the upper terminal, and means pivotally connecting one of said conductive means to said tube, said pivotally connected conductive means being adapted for displacement upon the blowing of the fuse to release the upper conductive means from the upper terminal.

11. A fused cutout as claimed in claim 10, wherein said spring means is associated with the lower terminal and yieldingly urges the same towards the upper terminal.

12. In a fused cutout of the dropout type, the combination with a pair of vertically spaced terminals, an insulating support for said terminals, the upper terminal comprising a pair of rigid and parallel arms forming a seat for receiving a fuse assembly and the lower terminal including means for pivotally supporting a fuse assembly, and spring means urging said terminals towards each other, of a fuse assembly comprising an expulsion tube having conductive means at the opposite ends thereof for engagement with said terminals, a fuse extending through said tube and electrically connected between said conductive members, said conductive means being spaced apart by a distance exceeding the normal spacing of said terminals, whereby said fuse unit is yieldingly retained between said terminals by a substantially axial pressure exerted thereon by said spring means, and means pivotally supporting one of said conductive means on said expulsion tube for displacement upon blowing of the fuse to release said fuse assembly from engagement with the upper terminal.

13. A fused cutout as claimed in claim 12, wherein said lower terminal is pivotally supported upon said insulating support, and said spring means urges said lower terminal towards the upper terminal.

14. A fused cutout as claimed in claim 12, wherein said insulating support comprises a casing of insulating material having an open front, in combination with a door for said casing secured to said fuse assembly.

15. A fused cutout as claimed in claim 12, wherein said insulating support comprises a casing having an open front, said upper terminal being rigidly secured to said casing and said spring means urging the lower terminal towards said upper terminal.

16. In a switch type of drop out fuse of the character described, a support of insulating material, a pair of terminals carried by said support, each terminal having means for receiving a fuse unit and one terminal including a flat spring member for urging said terminals towards each other to exert pressure upon and substantially along said fuse unit, and a fuse unit detachably supported by said terminals, said fuse unit including a pivoted member operable upon blowing of the fuse to permit the fuse unit to drop away from one of said terminals.

17. A drop out fuse of the type including an insulating support, a pair of spaced terminal members mounted on said support, a fuse unit pivotally supported on the lower terminal member and detachably engaged with the upper terminal member, and spring means urging said terminal members towards each other to exert a pressure substantially axially of a fuse unit mounted between the terminal members, characterized by the fact that said spring means comprises a flat spring member secured to said support and carrying one of said terminal members.

18. A drop out fuse as claimed in claim 17, wherein said spring means comprises a flat spring member secured to said support, and said lower terminal member is a hinge member secured to said spring member and constituting a pivotal support for the fuse unit.

19. In an enclosed fused circuit breaker, the combination with an insulating casing, a door for said casing, means pivotally supporting said door on said casing, and vertically spaced terminal means secured to said casing, of a fuse assembly carried by said door, said fuse assembly including an expulsion tube and conductive means for engagement with said terminal means when the door is closed, a fuse element extending through said tube and electrically connected between said conductive means, one of said terminal means including a flat spring for exerting pressure substantially along said fuse assembly to latch said

door and fuse assembly in approximately vertical position.

20. A dropout fuse switch comprising a housing, line terminals therein, one element of a hinge therein, a removable fuse cartridge having terminal engaging elements adapted to associate with said line terminals, a removable door for the housing carried by the cartridge, a second element on said hinge associated with said cartridge, a fuse link extending through said cartridge and electrically connected between said terminal engaging elements, resilient means associated with said housing adapted to press said cartridge to prevent movement of the cartridge and door away from closed position but permitting such movement when the fuse link is blown, the gravity effect of the door aiding that of the cartridge upon opening movement.

GEORGE L. CARLISLE.
